United States Patent

Des. 241,788
Patented Oct. 12, 1976

241,788

APRON

Jeanette Witzig, 2905 E. 65th St.,
Long Beach, Calif. 90805

Filed Nov. 6, 1974, Ser. No. 521,249

Term of patent 14 years

Int. Cl. D2—02

U.S. Cl. D2—229

Fig. 1

Fig. 2.

Fig. 3.

Fig. 4.

FIG. 1 is a front elevational view of an apron showing my new design with the slide fastener in partially opened condition;

FIG. 2 is a rear elevational view;

FIG. 3 is a right side elevational view; and

FIG. 4 is a top plan view.

I claim:

The ornamental design for an apron, as shown and described.
